UNITED STATES PATENT OFFICE.

DAVID T. SHARPLES, OF WEST CHESTER, PENNSYLVANIA, ASSIGNOR TO THE SHARPLES SEPARATOR COMPANY, OF WEST CHESTER, PENNSYLVANIA, A CORPORATION OF PENNSYLVANIA.

CENTRIFUGAL SEPARATOR.

Application filed April 23, 1925. Serial No. 25,335.

This invention relates to improvements in centrifugal separators, and has more particularly for its purpose the provision of a driving head construction.

5 One of the objects of this invention is to provide a driving head which may be swung out of line with the separator bowl to render possible a withdrawal of the bowl in a vertical direction, without interference by any 10 part of the driving head.

Another object is the provision of a power 15 system for the driving head of a centrifugal separator, in which a belt is utilized to drive selectively loose or tight pulleys. The loose pulley is mounted on a stub shaft in invariable position, while the tight pulley is secured to the main shaft of the driving head, and may be swung with the driving head out 20 of alinement with the stub shaft for the loose pulley.

A further object is the provision of a driving head containing within itself the speed 25 ratio gearing and elements, and comprising a unit which may be readily driven by a belt when in the operative position, and which, when in the operative position, and which, when the said belt is removed from cooperation therewith, may be readily swung to an inoperative position, in which it is out of 30 alinement with the centrifugal bowl and its jacket.

A further object is the provision of an improved driving system for the spindle of a centrifugal separator, by which a tendency of such spindle to move laterally and out of 35 engagement with the driving gear is avoided.

In this way, the spindle is assured against any tendency to whip or bend from the correct linear position: and is given a uniform, automatically balanced drive.

40 With these and other objects in view, there is represented on the accompanying drawing: Figure 1, a side elevation of the centrifugal separator showing in dotted lines the relative positions of the driving gearing, and in dash and dot-and-dash lines, two other possible positions for the driving head;

Fig. 2 a top plan view of the separator head with the cover plate removed to more clearly present the driving elements; and having a secondary position of the driving head represented in dot-and-dash lines;

Fig. 3 a diagram showing the relations of the several elements constituting the driving system; and

Fig. 4 a detail sectional view of the raising 55 mechanism.

In these drawings, J represents the jacket of a centrifugal bowl separator having associated therewith a sleeve S by means of the integrally cast web W. The driving head is 60 represented generally by the reference letter H. A tight pulley T furnishes power to the driving head when operatively engaged by the driving belt B. This driving belt B when it is not desired to operate the separator, is 65 moved on to the loose pulley L. The driving head H is preferably formed of a casting having side and end walls and bottom integral with each other. The cover C is bolted upon this base casting. The whole provides a 70 guard for the moving gears and prevents any throwing of oil or possibility of injury by contact with the gears. In the base casting are appropriately formed the bearings and 75 apertures to accommodate the various shafts and gears, as will be set forth hereinafter.

The driving head H is carried upon the spindle 1 received within a circular bore hole in the sleeve S. This spindle is provided with a series of teeth which extend around its 80 whole periphery as shown by the broken-away section in Fig. 4. This spindle is mounted in the sleeve S in such manner as to be secured against any downward movement 85 relative thereto during the raising and swinging of the driving head H; and is received at its upper end in a bore hole 2 formed within a sleeve 4 forming part of the integral casting constituting the shell or base of the driving head H. When the driving head H is in 90 its lowered position, a notch 3 in the lower edge of the sleeve 4 receives the lug 5 on the upper edge of the sleeve S, to lock the driving head in a predetermined position, in which the driving connection G is in axial 95 alinement with the jacket J and the centrifugal bowl X to be rotated therein. This assures a positive alinement of these members. P are the discharge pans or spouts.

In order to be able to swing the driving head H about the spindle 1, a lifting mechanism is provided for the driving head, and including the operating handle 6, which is journaled in an offset lug 7 on the downwardly extending sleeve 4 of the driving head H. A pinion 8 is pinned fast on the inner end of the shaft forming the pivot for the handle 6. This pinion 8 engages with the 100 105

teeth on spindle 1 through an aperture 9 in the sleeve 4, and when the handle is turned from the position shown at 6 in solid lines in Fig. 1, to the position shown at 6^a in dash lines in Fig. 1, the whole driving head is raised from the position shown in full lines to the position shown in dash lines.

In order to securely hold the driving head in a lowered position during the operation 10 of the separator, the sleeve 4 is slotted at 4^a (Fig. 2), and has the lugs 10 at either side of the slot. A handle 11 terminating in a threaded shaft and having a collar 12 is passed through the aperture in one of these 15 lugs, and is threaded into the other lug. As the handle 11 is rotated, the screw threads upon its shaft engage in a threaded lug 10, and by reaction with the collar 12, pinch the two sides of the split sleeve 4 and clamp it 20 tightly upon the spindle 1.

The driving system for the driving head comprises a tight pulley T which is mounted and keyed upon a shaft 20 (Fig. 3) which is journalled at 21 and 22 in the side walls of the 25 driving head H, and carries within the cavity of the driving head, the oppositely directed skew gears 23 and 23'. The shaft 20 is free to move endwise for a slight distance for a purpose which will be described hereinafter. 30 Meshing with the respective skew gears 23 and 23' are the two similarly cut skew gears 24 and 25 having a smaller number of teeth to provide a higher rotational speed of these gears 24 and 25 than the rotational speed of 35 the shaft 20. These gears 24 and 25 are mounted respectively on the two shafts 26 and 27 which are parallel to each other, and at right angles to the shaft 20. These shafts 26 and 27 are journalled at 28, 29, 30 and 31 in 40 the side walls of the main casing of the driving head H.

It is preferred to provide conical bearings for the ends of these shafts to assure accuracy of elements: and in order to assure the proper 45 lengthwise adjustment and precision of the bearings, these bearings 28, 29, 30 and 31 are formed as threaded plugs which may be screwed in or out for adjustment in the side walls of the driving head H, as shown in Fig. 50. These shafts 26 and 27 likewise carry the large worm gears 32 and 33 which mesh with the driving spindle 34 at opposite sides. The driving spindle is thus supported at each side against any tendency to move away from the 55 driving worm gears, so long as the worm gears 32 and 33 bear with equal pressure upon the spindle 34.

In order to compensate for any inequality in the driving pressure exerted by the worm 60 gears 32 and 33 upon the spindle 34, which would tend to cause a movement of the spindle 34 away from the worm gear, for example, that at 32, delivering the greater driving pressure, the two skew gears 24 and 25 65 are cut in opposite directions, and the shaft

20 is permitted an endwise movement as already referred to.

In operation, if, for example, the worm gear 32 is delivering a greater driving pressure than the worm gear 33, there is a greater reaction upon the shaft 26 than upon the shaft 27. In some cases, the total driving load may be assumed by one worm gear and shaft to the exclusion of the other. The situation then is the same as with a single worm gear drive, and the spindle 34 tends to move away from worm gear 32 at its portion opposite this gear. The shaft 26 communicates its reaction to the skew gear 24, which in turn re-acts upon the skew gear 23. Since the driving pressures between the meshing teeth of the skew gears 24 and 23 is greater than the corresponding driving pressures between the skew gears 25 and 23', the skew gear 23 tends to move axially and carry the shaft 20 along with it, by reason of the obliquity of the line of pressure at the teeth of the skew gears. However, as the gear 23' is pulled by the shaft 20, it moves bodily with its skew teeth until these skew teeth are pressed more strongly against the meshing teeth on the skew gear 25. This causes a corresponding forward movement to be made by the shaft 27, and thence by the worm gear 33 upon the spindle 34 until the driving pressures of the two worm gears 32 and 33 are once more balanced. It is apparent that as the worm gear 23 moved with its shaft, the driving pressure upon the worm gear 32, is, in this case relieved by a relative lengthwise slip of the teeth on the gears 23 and 24: and on the contrary, by the bodily movement of the skew gear 23 with regard to skew gear 25, the driving pressure upon the shaft 27 is correspondingly increased. An automatic balance of the driving forces is thus assured, so that the worm gears 32 and 33 immediately are compensated in case of any difference in driving pressures between them with regard to the spindle 34 and that this tendency to 100 compensate or balance exists only so long as there is a difference in the respective driving efforts.

The spindle 34 is journalled at 40 in the base casting of the driving head H, and carries the bowl connection G at its lower end through an aperture 41.

After operation of the separator, (the belt being on the loose pulley), the driving head H may be released by the handle 11 from its spindle 1. The bowl connection G is then released, and the whole driving head raised by means of handle 6, the pinion 8 and the teeth on the spindle 1 to disengage lug 5 from notch 3. The driving head may now be swung around the spindle 1 as a pivot into the position shown in dot-and-dash lines in Figures 1 and 2. It will be noted that there is no disturbance of the relation of the jacket and the belt or loose pulley during this opera- 130

tion: and yet, the entire top of the jacket and its bowl and pans are exposed for easy removal of the bowl and pans.

It is obvious that this invention is in no wise limited to the specific forms of construction shown, but that any modifications therein may be made within the scope of the appended claims.

Having thus described the invention, what I claim as new and desire to secure by Letters-Patent, is—

1. In a centrifugal separator, a vertical stationary jacket, a centrifugal bowl disposed therein, a driving head having a bowl connection and mounted for pivotal movement with regard to said jacket, means to positively aline said bowl connection with said bowl, means to lock said head and said bowl in alinement and means to disengage said alining means following release of said locking means and to permit movement of said driving head to a position in which it allows the upward withdrawal of said bowl from said jacket.

2. In a centrifugal separator, a vertical stationary jacket, a centrifugal bowl disposed therein, a vertical spindle mounted on said jacket, a driving head having a bowl connection and mounted for movement about the axis of said spindle when in a raised position, means for raising and lowering said driving head with respect to said jacket, and means to positively aline said bowl connection with said bowl in the lowered position of said driving head.

3. In a centrifugal separator, a vertical stationary jacket, a centrifugal bowl disposed therein, a vertical spindle mounted on said jacket, a driving head having a bowl connection and mounted for movement about the axis of said spindle when in a raised position, means for raising and lowering said driving head on said spindle, and means for locking said driving head in a predetermined lowered position.

4. In a centrifugal separator, a vertical stationary jacket, a centrifugal bowl disposed therein, a vertical spindle mounted in an aperture of said jacket and having a series of peripheral teeth therein, a driving head having a bowl connection and mounted for movement about the axis of said spindle, a pinion journaled in engagement with said teeth, and means to rotate said pinion to raise and lower said driving head with respect to said jacket.

5. In a centrifugal separator, a vertical stationary jacket, a centrifugal bowl disposed therein, a vertical spindle mounted on said jacket and having a series of peripheral teeth therein, a driving head having a bowl connection and mounted for movement about the axis of said spindle when in a raised position, a pinion journaled for rotation upon said driving head and in engagement with

the teeth on said vertical spindle, and a handle to rotate said pinion to raise and lower said driving head on said spindle.

6. In a centrifugal separator, a vertical stationary jacket, a centrifugal bowl disposed therein, a vertical spindle mounted on said jacket and having a series of peripheral teeth therein, a driving head having a bowl connection and mounted for movement about the axis of said spindle when in a raised position, a pinion journaled for rotation upon said driving head and in engagement with the teeth on said vertical spindle, a handle to rotate said pinion to raise and lower said driving head on said spindle, and means for positively alining said bowl connection and said bowl.

7. In a centrifugal separator, a vertical stationary jacket, a centrifugal bowl disposed therein, a spindle mounted on said jacket, a driving head having a bowl connection mounted for movement about the axis of said spindle, a loose pulley journaled in fixed relation to said jacket, a tight pulley associated with said driving head to furnish power to the same, said driving head in one position presenting said tight pulley in axial alinement with said loose pulley and said bowl connection in axial alinement with said bowl, and in another position said tight pulley being out of line with regard to said loose pulley, and said driving connection being out of line with said bowl, said driving head in the latter position permitting free upward withdrawal of said bowl from said jacket.

8. In a centrifugal separator, a vertical stationary jacket, a centrifugal bowl disposed therein, a driving head having a bowl connection and a tight pulley, a loose pulley journaled in fixed relation to said jacket, means to hold said driving head to present said bowl connection in alinement with said bowl and said tight pulley in alinement with said loose pulley, and means to release said holding means whereby said driving head may move with said tight pulley and said driving connection out of said respective alinements and into a position liberating said jacket for vertical withdrawal of said bowl.

9. In a centrifugal separator, a driving shaft with permissive endwise movement, a pair of oppositely directed driving skew gears on said driving shaft, a driven spindle having a worm, a pair of worm gears meshing with said worm and mounted on different sides thereof, a driven skew gear operatively associated with each of said worm gears, said driving skew gears meshing with said driven skew gears to drive the same, whereby the endwise movement of said driving shaft and the rotation of the driven skew gears determined thereby will equilibrate the driving pressures of said worm gears on said worm.

10. In a centrifugal separator, a driving shaft with permissive endwise movement, a pair of oppositely directed driving skew gears on said driving shaft, a driven spindle 5 having a worm, a pair of worm gears meshing with said worm and mounted on different sides thereof, a driven skew gear operatively associated with each of said worm gears, said driving skew gears meshing with said driven skew gears to drive the same, the method of equilibrating the driving pressures of said worm gears on said worm which consists in causing a greater driving pressure at one worm gear to effect an endwise movement of said driving shaft and opposite rotation of said driven skew gears relative to the respective driving skew gears.
11. In a centrifugal separator, a centrifugal bowl, a driving shaft, a worm spindle 20 to drive said bowl, a plurality of gear trains transmitting movement from said driving shaft to said worm spindle, and means to balance the driving effort of said gear trains.
12. In a centrifugal separator, a centrifugal bowl, a driving shaft, a worm spindle 25 to drive said bowl, a plurality of gear trains transmitting movement from said driving shaft to said worm spindle, and means to balance the driving effort of said gear trains.
13. In a centrifugal separator, a vertical stationary jacket, a centrifugal bowl contained in said jacket for rotative operation and removable by a vertical movement therefrom, a vertical spindle mounted on said jacket, a driving head having a separable driving connection for said bowl, said head normally preventing withdrawal of said bowl when separated from said head, a support for said head to pivotally mount said head on said spindle eccentric to the bowl axis so that the head in a first position is above said bowl and may be connected thereto to drive the same and in another position leaves a clear space above said bowl whereby the latter may be withdrawn vertically, and means on said head and support to positively align said bowl connection with said bowl in said first position.

In testimony whereof, I affix my signature.
DAVID T. SHARPLES.
